(57) **CLAIM**

The ornamental design for a bus, as shown and described.

DESCRIPTION

FIG. 1 is a top, front and right side perspective view of a bus according to an embodiment;

FIG. 2 is a front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The broken lines in the drawing depict portions of the bus that form no part of the claimed design.

1 Claim, 6 Drawing Sheets
